COMBINED CONTAINER OPENER AND
KNIFE SHARPENER

Leonard R. Kortick, 88 Waldron Ave., Cranston, R.I.

Filed Jan. 18, 1960, Ser. No. 59,089

Term of patent 14 years

(Cl. D44—29)

FIG. 1

FIG. 2

FIG. 3

Fig. 1 is a plan view of a combined container opener and knife sharpener embodying my new design.

Fig. 2 is a side elevation thereof.

Fig. 3 is a bottom view thereof.

I claim:

The ornamental design for a combined container opener and knife sharpener, as shown.
